(57) **CLAIM**

I claim the ornamental design for a swimming pool skimmer basket, as shown and described.

DESCRIPTION

FIG. 1 is a perspective view of a swimming pool skimmer basket, showing a first embodiment of my new design; FIG. 2 is a front elevational view of FIG. 1; FIG. 3 is a rear elevational view of FIG. 1; FIG. 4 is a right-side elevational view of FIG. 1, the left-side elevational view being a mirror image thereof; FIG. 5 is a top plan view of FIG. 1; FIG. 6 is a bottom plan view of FIG. 1; FIG. 7 is a perspective view of a second embodiment; FIG. 8 is a front elevational view of FIG. 7; FIG. 9 is a rear elevational view of FIG. 7; FIG. 10 is a right-side elevational view of FIG. 7, the left-side elevational view being a mirror image thereof; FIG. 11 is a top plan view of FIG. 7; FIG. 12 is a bottom plan view of FIG. 7; FIG. 13 is a perspective view of a third embodiment; FIG. 14 is a front elevational view of FIG. 13; FIG. 15 is a rear elevational view of FIG. 13; FIG. 16 is a right-side elevational view of FIG. 13, the left-side elevational view being a mirror image thereof; FIG. 17 is a top plan view of FIG. 13; FIG. 18 is a bottom plan view of FIG. 13; FIG. 19 is a perspective view of a fourth embodiment; FIG. 20 is a front elevational view of FIG. 19; FIG. 21 is a rear elevational view of FIG. 19; FIG. 22 is a right-side elevational view of FIG. 19, the left-side elevational view being a mirror image thereof; FIG. 23 is a top plan view of FIG. 19; and, FIG. 24 is a bottom plan view of FIG. 19.
